UNITED STATES PATENT OFFICE.

FRANK A. KLAVON AND JAMES J. KLAVON, OF PITTSBURGH, PENNSYLVANIA.

ROLLER-BEARING.

1,372,146.

Specification of Letters Patent. Patented Mar. 22, 1921.

Application filed May 22, 1920. Serial No. 383,372.

To all whom it may concern:

Be it known that we, FRANK A. KLAVON and JAMES J. KLAVON, residing at Pittsburgh, in the county of Allegheny and State 5 of Pennsylvania, both citizens of the United States, have invented or discovered certain new and useful Improvements in Roller-Bearings, of which improvements the following is a specification.

10 Our invention relates to improvements in roller bearings and is directed to improvements in durability and in efficiency.

It is illustrated in the accompanying drawings. Figure I is a plan view and Fig. II 15 a view in vertical section, on the plane indicated at II-II, Fig. I, of a head member of a cage for roller bearings. Fig. III is a view in perspective of a bearing plate, a succession of which is applied to each head 20 member of the cage. Fig. IV is a view in perspective of a roller bearing in the simplest form in which our invention is practised. Fig. V is a like view of a tie bar for the cage. Fig. VI is a view in longitudinal section of 25 the bearing structure complete, the bearing rollers in place in the cage, assembled with parts between which the bearing is arranged for service. Figs. VII, VIII, IX, and X illustrate various forms which the bearing 30 roller itself may assume, and herein are further specific features of invention. These four figures last named show the bearing roller in side elevation, excepting only Fig. IX, which shows it in longitudinal section. 35 Figs. XI and XII illustrate the invention applied to constitute a thrust bearing, Fig. XI being a view corresponding to Fig. VI of the bearing structure and showing a shaft in proper relative position, and Fig. XII 40 being a plan view of the bearing structure. Figs. XIII and XIV are views corresponding to Figs. XI and XII, and showing a modification in structure.

The structure as shown in Figs. I-VI inclusive consists of a cage made up of opposite heads 1, tie bars 2, and bearing plates 3, and of roller bearings 4. The heads 1 are conveniently stamped from sheet metal, the blanks being formed with lugs 5 which, 45 being bent to the shape indicated in the drawings, form separate confining spaces for

opposite ends of the individual rollers. Openings 6 are formed in the medial webs of the head members, for the securing of the ends of the tie bars 2, in the assembling of the 55 cage. In each interval between the opposite pairs of bent-up lugs 5, the medial webs are provided with a bearing plate 3 applied by riveting, spot-welding, or in equivalent manner. Each plate consists essentially of an 60 outwardly convex, conveniently spherical boss 7, so arranged that, when the parts are assembled, the rollers at their opposite ends engage these bosses tangentially in the lines of their axes. The opposite ends of each 65 roller 4 are rounded to spherical contour as indicated at 8.

The structure thus far described, in that it is provided with the convex bosses integral 70 with the cage, is improved both in the matter of diminution of friction, and in the matter of durability; the bearing of roller upon cage is concentrated in a point of contact, as distinguished from the usual more extended surface contact; the bodies which 75 so make contact are hardened to the work; and the portions of the cage which receive the strain distribute it.

Another feature, which may be super-added to that already described, is illustrated in Figs. V-VII of the drawings, and it concerns the particular construction of the bearing roller. It is shaped, as these figures show to the superficial configuration of a succession of transverse ridges of 85 curved cross section, specifically, as shown, to the configuration of a helix of round wire. Preferably it is a helix of round wire. The effect of this feature is that the roller, instead of making line contact with 90 the adjacent surface, makes tangential contact in a succession of points, and to the extent approaches more nearly, in form and in benefit, a ball bearing. If, as is preferred, the roller be actually made of wire 95 wrapped to a helix, the roller will possess a flexibility, such as to adapt it peculiarly to certain uses. In Fig. VII the roller will be seen to be a helix formed of round wire, wrapped upon itself as a fore. Flexibility 100 will manifestly be greater than in the case of a solid roller of equal over-all diameter.

It will be carefully noted that the ends of the roller so formed are rounded at 8, to co-operate with the bearing plates 3 of the cage, as already described. The roller of Fig. VIII is essentially a coreless helix (and as such still more flexible), and in the central space at opposite ends are introduced the shanks of round-headed bolts 9. The shanks of these bolts may be longer or shorter; they must be sufficiently anchored, but, beyond that, the degree of flexibility of the roller as a whole will depend upon their extent. It will further be observed of the roller of Fig. VIII that, in consequence of the construction described, the shanks of the two bolts 9 being discontinuous, the roller as a whole possesses a flexibility which it would not possess if the core were continuous. Indeed, if desired the parts may be so proportioned that there is a vacant space left within the helix, and to that extent it is a coreless helix. And in consequence of the fact that it is hollow within, its flexibility is at a maximum. In Fig. IX the helix is in its formation coreless, as in Fig. VIII: a removable and preferably one-piece core is inserted, in the form of a bolt 12; this bolt is slightly shorter than the helix, to afford terminal depressions which constitute seats for balls 11, and the ends of bolt 12 are preferably rounded. The balls 11 seated in the terminal depressions as shown in the drawing will bear in tangential contact upon the rounded ends of bolt 12 and when the roller is assembled these balls will bear upon bosses 7 in the supporting frame. The roller of Fig. X is conical. In this instance the conical helix is in its formation coreless, as the helices of Figs. VIII and IX, and is provided with a removable core, in the form of a bolt which protrudes beyond the helix at opposite ends and is round-ended, to bear upon the bosses 7 of a cage. Manifestly these various features of Figs. VII-X are interchangeable, with adaptations which are obvious, whether the helix be cylindrical or non-cylindrical.

The helical form of the roller is further advantageous, in that it is peculiarly effective to automatically distribute throughout its length lubricating oil applied to it at any point.

Figs. XI and XII show a conical roller, in this instance plane surfaced, though it too might be formed with the helical surface of Fig. X, applied to constitute a thrust bearing. The cage here is an annular box, its opposite heads inwardly inclined and provided with openings through which the conical rollers protrude, as the drawings show. This box is formed in two parts meeting in medial plane, and conveniently secured one to another by means of a boss, in the form of a bearing plate 7^a arranged within around the outer wall. This bearing

plate is of suitable dimensions and strength, is formed of suitable hardened material and is round-faced inwardly as shown, to the end that the areas of contact between roller and plate shall be brought to and continue at a minimum. Fig. XI shows a shaft S with convex end engaging the bearing, and it will be understood that on the opposite side the rollers will bear upon a corresponding surface, to sustain the thrust.

Figs. XIII and XIV show the same structure, except that the casing here is modified in its manner of formation. The box is not made of duplicate parts closing together in medial plane, but is an integral structure; one head 13^a is formed as in Fig. XI, and the opposite head is formed by the bending over of the lugs 14, which lugs are formed integral with the head 13^a. The boss 7^a is present, and in all other respects the structure is the same as that of Figs. XI and XII.

In certain of the ensuing claims we define the bearing roller to be made of round wire coiled to a helix. In using the term round wire we do not mean necessarily to be limited to a wire which is truly circular in cross section. It will be understood that all of the benefits and advantages herein described will be achieved in a helix made of a wire of which the external surface is in cross section of convex curvature. Ordinarily a wire of circular section will be employed if only because it is readily obtainable and relatively inexpensive.

We have already intimated, and now repeat, that the various features of invention shown in alternative form are freely interchangeable, with such adaptations as are obvious; and it will further be understood that modification in details are permissible, within the limits defined in the ensuing claims.

We claim as our invention:

1. A bearing structure for rotary machine parts consisting of a cage and of a plurality of rollers borne in said cage, said cage including opposite heads formed of sheet metal and consisting each of a medial web and bent-up roller-retaining lips, and provided with bearing plates applied to the medial web in the intervals between the bent-up lips, substantially as described.

2. A bearing structure for rotary machine parts including a cage, a convex boss borne by said cage, a bearing roller formed of a central convex-ended core and an enveloping helix extending beyond the end of the core and forming with the core a terminal ball seat, and a ball arranged within such seat and bearing upon the convex boss borne by said cage, substantially as described.

3. A roller bearing of which the individual roller consists of a helix of round wire adapted to make tangential contact with a

bearing surface, and responsive by virtue of its hollow core to flexure strains, substantially as described.

4. A roller bearing of which the individual roller consists of a helix of round wire adapted to make tangential contact with a bearing surface and provided with terminal bearing bolts whose shanks entering the hollow core of the helix from opposite ends

leave the helix flexible at an intermediate point to flexure strains.

In testimony whereof we have hereunto set our hands.

FRANK A. KLAVON.
JAMES J. KLAVON.
